(57) **CLAIM**

I claim the ornamental design for a reinforcement ring for beverage capsule, as shown and described.

DESCRIPTION

FIG. 1 is a top perspective view of a reinforcement ring for beverage capsule of the present invention;

FIG. 2 is a bottom plan view thereof;

FIG. 3 is a top plan view thereof;

FIG. 4 is a transverse section view thereof, taken along line 4-4 of FIG. 3; and,

FIG. 5 is a side elevation view thereof, with all other side views looking the same.

Broken lines and/or lighter-weight lines are used in FIGS. 1-5 to show contours most clearly viewable in FIG. 1.
